ROLL GRINDING MACHINE

Carl G. Flygare and Hugo B. Friberg, Worcester,
Mass., assignors to Norton Company, Worcester,
Mass., a corporation of Massachusetts

Application December 31, 1934, Serial No. 759,948

16 Claims.

(Cl. 51—94)

This invention relates to grinding machines for grinding large rolls, such as used in rolling mills, and more particularly to a forming or crowning attachment for producing a predetermined crown in the surface of the roll.

In rolling mill operations, it is necessary that the periphery of the rolls between which the metal is rolled be provided with a surface having the proper crown as well as a mirror finish, since any irregularities or imperfections in the surface of the roll are reproduced in the product rolled by the mill. It is, therefore, essential that the periphery of the roll be ground to a mirror surface of desired quality, as well as to be ground with a predetermined crown on its periphery so that when the two opposed rolls are mounted in the rolling mill, they will produce a product rolled therebetween which meets the required specifications.

Heretofore, numerous forming or crowning attachments have been developed and utilized in the grinding of rolls to produce the desired curvature on the surface of the rolls. Various types of mechanisms have been utilized including flexible forming bars, rigid forming bars, and also adjustable supports for the roll being formed which enable the axis of the roll to be skewed relative to the axis of the wheel.

It has been found through years of experience and numerous tests which have been conducted with the various roll forming attachments which are now utilized, that there is a bending or flexing of the swivel table supporting the roll during grinding, due to the pressure exerted by the forming apparatus and the pressure of the grinding wheel. It has been proposed to overcome such difficulties by means of the construction shown in the U. S. patent to H. W. Dunbar and Carl G. Flygare, No. 1,970,000, dated August 14, 1934. This roll forming attachment depended upon a fluid pressure system, in which fluid under pressure was forced into cylinders on opposite ends of the table to cause a swiveling movement of the table as it reciprocated. This invention relates to an improvement in that construction, in that it provides a positively actuated control device which regulates the rotative crowning movements of the wheel and the work and thus insures that the work is ground to a predetermined shape.

It is the primary object of this invention to provide a roll crowning apparatus for a grinding machine in which a hydraulically actuated, mechanically permitted swiveling movement is

employed to produce a crown of the desired curvature.

It is another object of this invention to provide a suitable fluid pressure operated mechanism for causing a relative swiveling movement between the work supporting table and the longitudinally movable table and to provide a positive control mechanism for regulating the movement of the swivel table as caused by the fluid pressure system.

It is a further object of this invention to provide a pressure controlling device which serves to permit regulation of the fluid pressure within the system so that the table may be initially flexed or bowed before the grinding operation has been started.

In a massive roll grinding machine of the type to which the present invention relates, the headstock is a massive, heavy unit which is usually many times as heavy as the footstock. This differential of weight at opposite ends of the swivel table serves to cause a differential friction between the opposite ends of the swivel table and the longitudinally movable table which must be overcome by the forming attachment, in order that the curvature or crown at each end of the roll may be properly shaped. Hence, it is desirable to provide a suitable pressure control means so that the pressure applied to the cylinder at either end of the table may be varied as desired.

It is a further object of the present invention to provide a pressure control for the fluid pressure system which enables applying a variable pressure at either end of the swivel table, if desired, so that the variation in pressure serves to compensate for the varying friction between the parts and to prevent bowing of the table from its normally adjusted position.

One embodiment of this invention has been illustrated in the drawings, in which like reference numerals indicate like parts:

Fig. 8 is a diagrammatic showing of a modified 10 hydraulic system having a pressure control valve which permits a variation in the fluid pressure passing to cylinders at opposite ends of the table.

This invention comprises broadly a roll grinding machine, in which the roll to be ground is 15 rotatably supported on a swivel table. The swivel table is pivotally mounted on a longitudinally movable work table which is arranged to be reciprocated longitudinally so as to carry the roll to be ground past the periphery of the grinding 20 wheel. A fluid pressure mechanism is interposed at opposite ends of the table between the longitudinally movable table and the swivel table to swing the swivel table relative to the longitudinally movable table as it reciprocates. A positively actuated mechanical control device is 25 provided to regulate and control the swiveling as caused by the hydraulic mechanism so as to produce a desired crown on the periphery of the roll being ground.

As illustrated in the drawings, one embodiment of this invention has been shown as adapted for a large, massive roll grinding machine comprising a base 10 having a longitudinally movable work table 11 reciprocably mounted on a flat way 12 and V-way 13 on the base 10. A grinding wheel 14 is rotatably mounted on a wheel slide (not shown) which is arranged for a transverse feeding movement relative to the table 11 by means of a manually or power operated wheel feeding mechanism 15. Details of the wheel feeding mechanism have not been illustrated, since they do not constitute a part of this invention. For details of construction as to the mounting of the grinding wheel and the construction of the wheel feeding mechanism, reference may be had to the prior U. S. patent to Norton No. 762,838 dated June 14, 1904. A swivel table 16 is pivotally connected to the longitudinally movable table 11 by a pivot pin 17 and is arranged so that the swivel 50 table 16 may swivel about the pivot pin 17 as the longitudinal table reciprocates so as to cause a relative transverse movement between the grinding wheel and the work and produce a desired crown upon the periphery of the work being ground. The swivel table 16 carries a rotatable work support including a headstock 18 and a footstock 19 which serve to rotatably support a work piece 20 on centers 21 and 22 respectively.

The longitudinally movable table 11 may be reciprocated longitudinally relative to the base by means of a manually operable hand wheel 25 or may be moved by a power actuated mechanism in which the table is automatically reversed by adjustable dogs 26 and 27 and a reverse control lever 28. For details of the manual traverse or power actuated reciprocating mechanism, reference may be had to the prior Norton Patent No. 762,838 above referred to.

Hydraulic crowning mechanism

In order that the swivel table 16 may be swivelled transversely in a horizontal plane relative to the longitudinal table 11 when the table reciprocates, a hydraulic mechanism is provided 75 to cause the desired transverse movement between

the tables so as to produce a desired predetermined curvature or crown on the periphery of the roll 20 being ground. The hydraulic mechanism is preferably a self-contained mechanism which is mounted on the reciprocable table 11 and consists of an electric motor 30 connected to a fluid pump 31. The pump 31 draws fluid through an intake pipe 32 from a reservoir (not shown) and delivers fluid through a pressure control or relief valve 33 through a pipe 34 and a reverse valve 35. The reverse valve 35 is arranged to convey fluid to opposite sides of a piston 36 which is slidably mounted in a cylinder 37. The cylinder 37 is fixedly mounted on the table 11, and the piston 36 is connected by a link 38 to an extending 10 bracket 39 formed as an integral part of the swivel table 16. It will thus be seen that admission of fluid under pressure to either side of the piston 36 will cause a swiveling movement between the longitudinally movable table 11 and 20 the swivel table 16.

In the preferred construction, a double fluid pressure actuating means is provided, such as illustrated in Fig. 2 of the drawings. Such a mechanism includes a fluid pressure piston and cylinder at the right-hand end of the table, which is identical in every respect to the piston and cylinder at the left-hand end. This mechanism comprises a cylinder 40 fixed to the table 11 and a piston 41 slidably mounted therein and connected by a link 42 with a projecting bracket 43 of the swivel table 16.

The reversing valve 35 is operatively connected with the cylinders 37 and 40 by means of pipes 45 and 46. The pipe 45 connects with the lower chamber 48 of cylinder 37 and the upper chamber 49 of cylinder 40, as viewed in Fig. 2. The pipe 46 is connected with the upper chamber 50 in cylinder 37 and the lower chamber 51 in cylinder 40, so that when pressure is applied to either the 40 pipe 45 or 46, the fluid under pressure serves to cause a swiveling movement of the table 16 relative to the reciprocable table 11 either in a clockwise or counterclockwise direction, as viewed in Fig. 2. In the position of the reversing valve 35, as illustrated in Fig. 2, fluid under pressure is being admitted through pipe 45 to cylinder chambers 48 and 49, so as to cause the swivel table 14 to move in a clockwise direction. The fluid pressure remains in this direction until the reverse valve 35 is shifted.

It is desirable to provide a suitable interconnection between the reciprocable table and the fluid pressure system so that when the table is moved in a direction toward the right (Fig. 2), the table 14 is moved in a clockwise direction. When the reversing mechanism is shifted to change the direction of movement of table 11, the fluid pressure reversing valve 35 is shifted to reverse the swiveling movement of table 14 so that during movement of table 11 towards the left (Fig. 2) the swivel table 16 is moved in a counterclockwise direction. This is preferably accomplished by an electrically controlled mechanism which, in the preferred construction, is interconnected with the table reversing mechanism so that when the adjustable dogs 26 and 27 actuate the reversing lever 28 to change the direction of movement of the table 11, this movement also serves to operate reverse valve 35 and thereby change the direction of flow of fluid pressure within the hydraulic system. To accomplish this result, a solenoid 52 is mounted on the table 11 and is connected to operate the reversing valve 35 in one direction, namely, downward- 75

ly, as shown in Fig. 2. A spring 53 serves to return the valve into the position illustrated in Fig. 2. A reversing switch 54 is connected by a link 55 with the reversing lever 28 so that when the switch is in the position as illustrated in Fig. 2, the circuit is open and the solenoid 52 is deenergized. When the reverse lever is shifted into the reverse position at the end of a table stroke, the reversing switch shifts into the position illustrated in the dotted line (Fig. 2), thereby energizing solenoid 52 and shifting the reversing valve 35 into a downward position (Fig. 2) so as to admit fluid under pressure through the pipe 46 into cylinder chambers 50 and 51 to cause the table to move in a counterclockwise direction. It will thus be seen that when the table 11 travels in one direction, the fluid pressure piston and cylinder serve to swivel the table in one direction and when moved in the opposite direction serve to swivel the table in the reverse direction.

Mechanically controlled swiveling movement

In order that the swiveling movement of the table 14 relative to the reciprocable table 11 may be accurately controlled, it is desirable to provide a positively actuated permitting or controlling mechanism which serves to restrict the movement of the table by the fluid pressure mechanism, so that instead of having a directly acting fluid pressure movement, a hydraulically actuated, mechanically permitted or controlled movement is provided. It is desirable to provide a suitable control mechanism which is actuated as the table reciprocates to positively control the swiveling movement of the swivel table 14 so as to produce a predetermined crown on the roll to be ground. In the preferred construction, a forming bar 60 is pivotally mounted on a stud 61 on the base 10 and is arranged to be adjusted angularly relative to the base, so that it may be positioned parallel with the movement of the reciprocating table 11 to grind a straight cylindrical roll, or it may be adjusted angularly relative to the table movement if it is desired to produce a crown on the periphery of the roll being ground. A slide 62 is carried by the bar 60 and is operatively connected by means of a bar 63 with a bracket 64 which is fixedly mounted to table 11. It will be readily appreciated from the foregoing disclosure and the illustration in the drawings that when the table 11 is reciprocated longitudinally relative to the base 10, the slide 62 is moved simultaneously by means of the bracket 64 and the rod 63.

In order that the fluid pressure system may be so controlled as to produce a predetermined crown or curvature on the roll being ground, a suitable, positively actuated, mechanically controlled or retreating stop mechanism is provided which in the preferred form comprises a rotatable screw 65 which is journaled in bearings 66 and 67 in the bracket 64. A partial nut 68 meshes with the screw 65 and is pivotally connected by means of a pin 69 to bracket 39 which projects from the end of the swivel table 14. It will be readily appreciated from this disclosure and the illustration in Figs. 5 and 7 of the drawings that rotation of the screw 65 relative to the nut 68 serves to definitely control and limit the swiveling movement of the table 14 relative to the table 11.

In order that the swiveling movement may be definitely controlled by and in timed relationship with the longitudinal reciprocation of the work

carrying member, a suitable connection is provided between the forming bar and the screw. The longitudinal movement of the slide 62 relative to bar 60 is transmitted to cause a predetermined rotary motion to the screw 65 so as to cooperate with the nut 68 and permit a predetermined swiveling movement of the table 14 relative to the table 11 by means of the fluid pressure piston 36. In order to control the rotary motion of the screw 65 to produce the desired crown on the surface of the roll, a rack bar 75 is slidably mounted within bracket 64 and is connected at its lower end with the slide 62. The rack bar 75 meshes with a gear 76 mounted on the outer end of the screw shaft 65. It will be readily appreciated from the foregoing disclosure and the illustration in the drawings that when the table 11 is reciprocated relative to the base, the slide 62 will be carried through a corresponding distance along the forming bar 60. This bar 60 is set parallel to the table movement; then no movement will be transmitted to allow or permit a swiveling movement of the table 14. If, however, the forming bar is adjusted angularly relative to the path of movement of the table 11, a movement of the slide 62 along the bar 60 will transmit a vertical motion to the rack bar 75 relative to the bracket 64 which is fixed to the end of the table 11, so as to transmit a rotary motion to gear 76 and screw 65 so as to permit a predetermined, positively controlled swiveling movement of the table 14 relative to table 11.

In order to prevent any backlash between the rack 75 and gear 76, a compensating mechanism is provided comprising a narrow, slidably mounted rack bar 77 which is slidably mounted in the face of the rack 75. This adjustable rack 77 may be adjusted relative to the rack 75 by means of a screw 79 fixed in the end of the rack bar 75 and nuts 80 and 81. By adjusting the nuts 80 and 81 relative to screw 79, any backlash between the rack and the gear may be eliminated.

The foregoing describes a single control unit at the left-hand end of the machine, as viewed in Figs. 1 and 2. In the preferred construction, an identical control unit is provided at the right-hand end of the machine, as illustrated in Figs. 1 and 2. This unit comprises a forming bar 85 pivotally mounted on the stud 86 and carrying a slide 87 thereon. The slide 87 is carried longitudinally by a bar 88 which is connected to the slide and is slidably mounted in a bracket 89 projecting from the right-hand end of table 11. A rack bar 90, also carried by slide 87, is slidably mounted in bracket 89 and meshes with a gear 91 mounted on the end of a screw 92 which meshes with a nut (not shown) on a bracket 93.

In the preferred adjustment of parts, the forming bars 60 and 85 are adjusted to the same angular position, so that when the table moves toward the right, as viewed in Figs. 1 and 2, the forming bars, slides and screws 65 and 92 together with their connecting parts serve to control the swiveling movement of table 14 relative to table 11 in a counterclockwise direction; and similarly, when the table is reversed in its direction of movement so that it moves toward the left, as viewed in Figs. 1 and 2, serve to transmit a rotary motion to screws 65 and 92 so as to control the movement of the swivel table 14 in a counterclockwise direction relative to table 11 to produce the desired predetermined crown on the periphery of the roll 20 being ground.

Pressure control device

In a massive roll grinding machine of the type illustrated in the drawings and to which this invention applies, the tables, headstock and footstock are massive, heavy parts. The headstock is several times heavier than the footstock, thereby causing a differential in friction between the swivel and longitudinally movable tables at their opposite ends. If equal pressures were applied to the cylinders at opposite ends of the table, this would result in possible flexing of the table from its normal path of movement, due to the fact that the frictional forces are greater at the headstock end than at the footstock end.

To attain one of the objects of this invention, namely, to provide a differential in the fluid pressure system which enables separate adjustment and regulation of the fluid pressure being applied to each cylinder at opposite ends of the table, a suitable pressure control valve is provided which permits applying a higher pressure to the cylinder 37 than that applied to cylinder 40, so that the differential in friction between the swivel and longitudinally movable tables may be equalized. In the preferred form, this mechanism (Fig. 8) comprises a modified piping and fluid pressure system including a pump 100 which is connected by pipe 101 with a pressure control valve 102. The pressure control valve is connected to a reverse valve 103 which is in turn connected to cylinders 37 and 40. Fluid from the pipe 101 enters the pressure control valve chamber 104 and passes through pipe 105 into reverse valve chamber 106 which, in the position illustrated in Fig. 8, passes fluid through pipe 107 into cylinder chamber 50. The valve member 108 is yieldably held in a closed position by a spring 109, the tension of which may be adjusted by screw 110. The screw 110 may be locked in adjusted position by lock nut 111. By manipulation of the adjusting screw 110, the tension of the spring 109 may be varied, so that the desired pressure will be maintained in pipe line 105, but so that if the pump pressure is greater than that required in line 105, the pressure is relieved by partially opening the valve 108. When valve 108 is opened, fluid under pressure passes through a passage 112 into chamber 113 through a pipe 114, valve chamber 115, pipe 116, into cylinder chamber 51. In the position of the valve illustrated in Fig. 8, the pistons 36 and 41 apply a force to the swivel table 14 tending to move the swivel table in a counterclockwise direction. A valve member 117 is backed by a spring 118, the tension of which may be adjusted by a screw 119 and lock nut 120, so that the pressure in the pipe line 114 may be varied as desired. If the pressure within the chamber 113 is greater than that required in the pipe line 114, the excess pressure will cause the valve 117 to open and the fluid to exhaust through pipe 121 into the reservoir.

It will thus be seen that by utilizing a modified construction, such as that shown in Fig. 8, the pressure applied at opposite ends of the swivel table to cause the desired swiveling motion may be varied to overcome the differential of friction between the swivel table and the longitudinally movable table.

Concave crown

In certain types of grinding, it is necessary to produce a concave crown on the periphery of the roll. When the bars 60 and 85 are adjusted

into position 60a and 85a, as indicated in Fig. 1, this adjustment operates through screws 65 and 92 to shift the position of the swivel table 14 so that at the start of the grinding operation, the end of the roll is farther away from the wheel axis and as the roll is traversed or reciprocated, the screws serve to swivel the table so as to produce a hollow or convex surface on the periphery of the roll. In order to assist in this reverse movement of the table, it is necessary and desirable that the fluid pressure system be reversed automatically without attention on the part of the operator, so that when the bars are in a position to concave the roll, the fluid pressure system serves to apply a swiveling movement to the table 14 so as to produce the desired concave surface on the periphery of the roll. To accomplish this result automatically, a reversing switch 130 is mounted on the base of the machine. This switch carries a reversing arm 131 having a roller 132 engaging a cam 133 which is adjustably fixed to the forming bar 60. This construction is diagrammatically indicated in Fig. 2 and shows the bar in the full line position, as indicated in Fig. 2, the roller 132 is on the low point of the cam 133. When the bar 60 is shifted into position 60a, the bar 60, as illustrated in Fig. 2, moves upwardly, carrying the cam 133 upwardly, which serves to rock the roller 131 and arm 132 of the reversing switch 130 so as to shift the movable switch member into the reverse direction, so as to reverse the operation of the fluid pressure system to enable the grinding of a concave surface on the roll being ground.

In setting up the forming attachment for grinding a given roll, it is desirable to apply a predetermined pressure at opposite ends of the table so as to bow or flex the table to take out the spring in the swivel table parts, so that during the operation of the machine, the swivel table is always under a flexing tension. In order to initially flex the table to a desired and predetermined extent, each of the rack bars 75 and 90 is adjustably connected to the slides 62 and 87 respectively. The lower end of each rod has a reduced threaded portion 136 which passes through an aperture in the slides 62 and 87 respectively. Nuts 137 and 138 are provided to locate the rack bars 75 and 90 respectively relative to the slides 62 and 87. By adjusting the nuts 137 and 138 at each end of the table, the racks 75 and 90 may be moved up or down, causing a rotation of the gears 76 and 91, which serves to flex or bow the swivel table 14 to place it under an initial strain to prevent any flexing of the table due to the movement transmitted thereto by the forming attachment or the thrust of the grinding wheel.

In the preferred form of this invention, the gears 76 and 91 are adjustably mounted on the screw shafts 65 and 92 and are held in adjusted position by lock nuts 135. This adjustment is identical on both mechanisms at the ends of the table, and consequently only details of the left-hand mechanism have been illustrated in Fig. 7. It will be readily appreciated from this construction that the operator may by striking off on the nuts, adjust the gears 76 and 91, so that they operate in synchronism.

The operation of this machine will be readily apparent from the foregoing disclosure. The operator places a roll 20 to be ground in the machine, supporting it on centers or in any well-known manner common to the roll grinding industry, such as journal rest supports; then ad-

justs the position of the forming bars 60 and 85 so as to produce a desired and predetermined convex or concave crown on the roll to be ground. The table reciprocation is started and as the table 5 11 reciprocates relative to the base 10, the swivel table 16 is rocked about the pivot 17 as an axis to vary the center distance between the axis of the work and the axis of the grinding wheel during reciprocation, so that either a concave or a 10 convex crown may be produced on the roll, as desired.

Having thus described the invention, what we claim as new and desire to secure by Letters Patent is:

15 1. A roll grinding machine having a rotatable grinding wheel and a rotatable work support which are movable transversely and longitudinally relative to each other, means to move one of said members relatively toward and from the other to 20 produce the desired feeding movement to grind a roll to a predetermined size, an additional mechanism operatively connected to cause an independent relative transverse movement between the wheel and work support as they are reciprocated 25 longitudinally relative to each other to grind a crown on the roll being ground, and a positively actuated control device independent of said mechanism which is actuated during the relative longitudinal movement between the grinding wheel 30 and work to positively control said independent relative transverse movement between the wheel and the work support as caused by said mechanism so as to produce a predetermined crown on the roll being ground.

35 2. A roll grinding machine having a rotatable grinding wheel and a rotatable work support which are movable transversely and longitudinally relative to each other, means to move one of said members relatively toward and from the other to 40 produce the desired feeding movement to grind a roll to a predetermined size, a fluid pressure mechanism operatively connected to cause an independent relative transverse movement between the wheel and work support as they are reciprocated 45 longitudinally relative to each other to grind a crown on the roll being ground, and a control device including a positively moved stop which is actuated during the relative longitudinal movement between the grinding wheel and work 50 to positively control the independent relative transverse movement of said members as caused by said fluid pressure mechanism so as to regulate and control the relative movement between the wheel and work support to produce a predetermined crown on the roll being ground.

55 3. A roll grinding machine having a rotatable grinding wheel and a rotatable work support which are movable transversely and longitudinally relative to each other, means to move one of said members relatively toward and from the other to 60 grind a roll to a predetermined size, an additional mechanism operatively connected to cause a relative transverse movement between the wheel and work support as they are reciprocated longitudinally relative to each other, and a control device including an adjustable bar and follower and a stop positively moved thereby which serve to regulate and control the relative transverse movement between the wheel and work 65 support so as to produce a predetermined crown on the roll being ground.

70 4. A grinding machine comprising a base, a transversely movable slide thereon, a rotatable grinding wheel supported on said slide, a longitudinally movable table on said base, a swivel table 75

pivotedly mounted on said first table, a rotatable work support on said swivel table, fluid pressure means interposed between said tables to cause the swivel table to swing relative to the longitudinally movable table as it reciprocates, and a positively actuated control device independent of the hydraulic mechanism which regulates and controls said fluid pressure operated swiveling movement of the swivel table as the longitudinally movable table reciprocates and so produces the 10 desired form on the roll being ground.

5 5. A roll grinding machine having a rotatable grinding wheel and a rotatable work support which are movable transversely and longitudinally relative to each other, means to move one of said members relatively toward and from the other to 15 produce the desired feeding movement to grind a roll to a predetermined size, a fluid pressure system including a piston and cylinder which are operatively connected to cause a relative transverse movement between the wheel and work support as they are reciprocated longitudinally relative to each other, and means including an adjustable bar and follower and a control device actuated by the follower and independent of 20 the fluid pressure mechanism which serves to regulate and control the relative movement between said members caused by said fluid pressure piston and cylinder so as to regulate and control the relative movement between the wheel and 25 work support to produce a predetermined crown on the roll being ground.

6. A grinding machine comprising a base, a transversely movable slide thereon, a rotatable grinding wheel supported on said slide, a longitudinally movable table on said base, a swivel table pivotedly mounted on said first table, a rotatable work support on said swivel table, a fluid pressure system including a piston and cylinder interposed between said tables to cause the swivel 30 table to swing relative to the longitudinally movable table as it reciprocates, a forming bar adjustably fixed on the base, and an independently actuated control mechanism and connections between said device and the bar, the longitudinally 35 movable table and the swivel table to positively control the extent of swiveling of said swivel table as the table reciprocates to produce the desired form on the roll being ground.

7. A grinding machine comprising a base, a transversely movable slide thereon, a rotatable grinding wheel supported on said slide, a longitudinally movable table on said base, a swivel table pivotedly mounted on said first table, a rotatable work support on said swivel table, a fluid pressure system including a piston and cylinder interposed between said tables to cause the swivel table to swing relative to the longitudinally movable table as it reciprocates, a forming bar adjustably fixed on the base, means including a nut and screw mechanism interposed between the longitudinally movable and swivel tables, and connections between said bar and screw to rotate said screw as the table is reciprocated to positively control the extent of swiveling of said 60 swivel table as the table reciprocates to produce the desired form on the roll being ground.

8. In a roll grinding machine having a transversely movable wheel slide, a longitudinally movable work table, a work supporting member pivotedly mounted on said table and arranged to rotatably support a roll in operative relation with the grinding wheel, and a forming apparatus including a bar adjustably positioned on the base, a slide carried by said bar as the table moves 65 70 75

longitudinally, a fluid pressure system including a piston and cylinder operatively connected between the ends of the longitudinally movable table and the swivel table, and means including 5 a nut and screw interposed between said longitudinally movable table and swivel table which are actuated by said slide as the table is reciprocated to positively control the swiveling movement of said table to produce the desired 10 crown or form on the periphery of the roll being ground.

9. A forming attachment for roll grinding machines comprising a transversely movable wheel slide, a rotatable grinding wheel thereon, a longitudinally movable table, a swivel table pivotally mounted on said movable table, a rotatable work support on said swivel table, a fluid pressure system including a piston and cylinder interposed between the longitudinal and swivel tables which 20 are arranged to cause a swinging of the swivel table as the longitudinal table is reciprocated, a fluid pressure pump arranged to convey fluid under pressure to either end of said cylinder, a control valve arranged to control the fluid pressure admitted to said cylinders, and a control device arranged to positively control and regulate the swiveling of said table so as to produce a predetermined crown on the roll being ground.

10. A roll grinding machine comprising a transversely movable wheel slide, a rotatable grinding wheel thereon, a longitudinally movable table, a swivel table pivotally mounted on said movable table, a rotatable work support on said swivel table which is arranged to rotatably support a roll in operative relation with the grinding wheel, a fluid pressure system including a piston and cylinder at each end of said table which are operatively connected between the ends of the longitudinally movable table and the swivel table to 40 cause a relative swiveling of the work support as the table is reciprocated, a fluid pressure pump arranged to force fluid to opposite ends of said cylinders respectively to cause the work support to swivel in one direction, a reversing valve arranged to reverse the flow of fluid in said system to cause the swivel table to swivel in the opposite direction, and means actuated in timed relation with the table movement to reverse said valve at each end of the table stroke.

50 11. A roll grinding machine comprising a transversely movable wheel slide, a rotatable grinding wheel thereon, a longitudinally movable table, a rotatable work support supported on said table which is arranged to rotatably support a roll in operative relation with the grinding wheel, a feeding mechanism to move said grinding wheel and work relatively toward and from each other to 55 grind the roll to a predetermined size, a fluid pressure system including a piston and cylinder at each end of said table which are operatively connected between the ends of said longitudinally movable table and said work support to cause a relative transverse movement therebetween as the table is reciprocated, and a fluid pressure control device which permits varying the fluid pressure conveyed to cylinders at opposite ends of the table.

70 12. A roll grinding machine comprising a transversely movable wheel slide, a rotatable grinding wheel thereon, a longitudinally movable table, a rotatable work support supported on said table which is arranged to rotatably support a roll in operative relation with the grinding wheel, a feeding mechanism to move said grinding wheel and work relatively toward and from each other 75

to grind the roll to a predetermined size, a fluid pressure system including a piston and cylinder at each end of said table which are operatively connected between the ends of said longitudinally movable table and said work support to cause 5 a relative transverse movement therebetween as the table is reciprocated, means including a forming bar arranged to positively control the relative transverse movement between the wheel and work, and a fluid pressure control device which 10 permits varying the fluid pressure conveyed to cylinders at opposite ends of the table.

13. A roll grinding machine comprising a transversely movable wheel slide, a rotatable grinding wheel thereon, a longitudinally movable work table, a swivel table pivotally mounted on said table and arranged to rotatably support a roll in operative relation with the grinding wheel, means to feed said slide toward and from the work support to grind a roll to a predetermined size, a fluid pressure system including a piston and cylinder operatively connected between the swivel and longitudinally movable tables, a pump to convey fluid to opposite ends of said cylinder, and a reversing valve operatively connected to change 25 the direction of flow of fluid in said system when the longitudinally movable table is reversed in its direction of movement.

14. A roll grinding machine comprising a transversely movable wheel slide, a rotatable grinding wheel thereon, a longitudinally movable table, a swivel table pivotally mounted thereon, a rotatable work support on the swivel table, a feeding mechanism to cause a relative transverse movement between the grinding wheel and the work, 30 means to reciprocate said table, and a forming apparatus including a fluid pressure system to swivel said table as it reciprocates including a piston and cylinder interposed between the swivel and longitudinally movable tables, and a control mechanism to positively control the fluid pressure swiveling of said table including a nut and screw mechanism interposed between the longitudinally movable and the swivel table, a forming bar adjustably mounted on the base, a slide slidably 40 mounted on said bar, and connections between the slide and the screw to rotate the screw as the table reciprocates to control the swiveling movement so as to produce a predetermined crown on the roll being ground.

50 15. A roll grinding machine comprising a transversely movable wheel slide, a rotatable grinding wheel, a longitudinally movable work table, a swivel table pivotally mounted thereon, a rotatable work support including a headstock and a 55 footstock on said swivel table, a feeding mechanism to cause a transverse movement of the grinding wheel relative to the work, a reciprocating mechanism to reciprocate said table, and a forming apparatus including a fluid pressure system comprising a piston and cylinder at each end of the table interposed between the longitudinally movable table and the swivel table, a pump for conveying fluid under pressure to said cylinders, a reversing valve actuated in timed relation with the table reciprocating mechanism to change the direction of flow of fluid in said system, a pressure control valve in said system which is arranged to permit independently varying the fluid pressure for each cylinder, and a 70 control device to positively control the swiveling movement of said table as caused by said fluid pressure mechanism including a nut and screw interposed between the swivel and longitudinally movable tables, an adjustable forming bar on the 75

base, a slide slidably mounted on said bar, and connections between said slide and screw to rotate said screw as the table reciprocates.

16. A roll grinding machine comprising a transversely movable wheel slide, a longitudinally movable work table, a swivel table pivotally mounted on said table, a massive headstock on one end of said swivel table, and a footstock on the other end of said swivel table to rotatably support a roll to be ground in operative relation with the grinding wheel, means to cause a transverse feeding movement of the grinding wheel slide toward and from the work support to grind the work to a predetermined size, means to reciprocate said work support longitudinally relative to the grinding wheel, a fluid pressure system including a piston and cylinder at each end of said table which are interposed between the swivel and longitudinally movable tables to cause a swiveling 10 of the swivel table as the longitudinally movable

table is reciprocated, a fluid pressure pump arranged to convey fluid to opposite ends of the respective cylinders to cause a swiveling movement in one direction when the table is traversed in one direction, a reversing valve to reverse the direction of fluid and cause the swivel table to be swiveled in the opposite direction when the table movement is reversed, means actuated in timed relation with the table reciprocation to reverse the direction of fluid movement when the table is reversed, and a pressure control valve which is so arranged as to permit varying the fluid pressure applied to the cylinders at opposite ends of said table so as to overcome the difference in friction between opposite ends of the table and the swivel table caused by the varying weights of the head and foot stock mounted thereon. 15
